UNITED STATES PATENT OFFICE.

FRANK RUDOLPHI, OF CHICAGO, ILLINOIS, ASSIGNOR TO AMERICAN CAN COMPANY, OF NEW YORK, N. Y., A CORPORATION OF NEW JERSEY.

DESIGN FOR A SHEET-METAL DISPLAY-CAN.

No. 39,120.

Specification for Design.

Patented Feb. 11, 1908.

Application filed May 31, 1907. Serial No. 376,740. Term of patent 14 years.

To all whom it may concern:

Be it known that I, FRANK RUDOLPHI, a citizen of the United States, residing at Chicago, in the county of Cook and State of Illinois, have invented a new, original, and ornamental Design for Sheet-Metal Display-Cans, of which the following is a specification, reference being had to the accompanying drawing, forming part thereof.

The figure is a front elevation of a sheet metal display can, showing my new design.

I claim:

The ornamental design for a sheet metal display can, as shown.

FRANK RUDOLPHI.
